UNITED STATES PATENT OFFICE

2,525,237

DROP FOOT BRACE

Marion A. Park, St. Louis, Mo.

Application November 16, 1949, Serial No. 127,649

2 Claims. (Cl. 128—80)

1

This invention relates to a support designed for use by patients suffering from various forms of paralysis, the primary object of the invention being to provide a support which will brace the leg, ankle and foot of the patient wearing the device, assisting in treating and preventing curvature of the spine, and at the same time rendering walking less difficult.

An important object of the invention is to provide a support designed to strengthen the metatarsal when the foot is weak, and has a tendency to fall from the front.

Still another object of the invention is to provide a brace which will be supported by the shoe worn by the patient, in such a way that the leg brace section of the device may pivot with the bending of the leg at the ankle, thereby relieving the support of undue pressure required when wearing the usual known leg braces.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing

Figure 1 is a perspective view of a support, constructed in accordance with the invention.

Figure 2 is an enlarged detail view illustrating the yieldable means employed in returning the foot to its normal position, after the bending of the foot in walking.

Referring to the drawing in detail, the reference character 5 indicates the shoe which is provided with a built-up sole 6 and a built-up heel 7 which is worn by the person using the support.

Fitted between the heel proper 7 and upper of the shoe, at the heel section thereof, is the plate 8 which includes inner right angled upwardly extended ears 9 and a rearwardly extended main arm 10 which is of a length to extend beyond the rear edge of the heel 7, as clearly shown by Figure 1 of the drawing.

The reference character 11 indicates the main supporting arm of the device, which has its lower end curved and bifurcated, the ends of the furcations indicated at 12 being pivotally connected to the ears 9, at 13.

Secured to the rear surface of the arm 11, near the lower end thereof, is the tubular housing 14 which has its lower end open providing a housing for the coiled spring 15 which has its upper end

2

bearing against the disc 16 against which the tensioning screw 17 engages, the tensioning screw operating through a threaded bore in the upper end of the housing.

5 The lower end of the coiled spring 15 is fitted over the enlargement 18 holding the lower end of the spring in position on the main bar 10, so that under normal conditions, the action of the spring 15 will be to move the shoe or foot of the person wearing the shoe, to a position at right angles to the main supporting arm 11. It will be obvious that as the shoe moves with the bending of the ankle of the person wearing the shoe, the spring will be placed under tension to urge the 15 shoe and foot to its normal position when the foot is raised in taking a step.

Secured at the upper end of the supporting arm 11, is the strap 19 which is substantially wide and constructed of soft rubber material for the comfort of the wearer. Secured to the strap 19, is a leather strap 20 which connects with the buckle 21 in securing the strap 19, around the leg of the person wearing the brace, the connection being made preferably directly below the knee of the 25 person wearing the brace.

While the brace is designed primarily for treating patients suffering from various diseases such as poliomyelitis, or infantile paralysis, it is to be understood that the device is also beneficial in strengthening the metatarsal, particularly when the foot has a weakness to fall from the front.

With the device forming the subject matter of the present invention, the tension of the spring may be regulated to meet various requirements and conditions, for the benefit of the person 35 using the device.

Having thus described the invention, what is claimed is:

1. A support comprising a plate secured between the heel and upper of a shoe, the plate extending beyond the heel portion of the shoe, a supporting arm pivotally connected to the plate adjacent to the front of the heel and being curved around the rear of the heel, a strap secured to the upper end of the arm and adapted to secure the upper end of the arm to the leg of the wearer, a tubular housing secured to the arm and disposed vertically, said housing having an open lower end, a coiled spring disposed within the open end of the housing and resting on the plate normally urging the plate and shoe to which the plate is connected, to a position at right angles with respect to the arm.
2. A support comprising a plate secured between the heel and upper of a shoe, the plate

55

extending beyond the heel portion of the shoe, a vertical supporting arm pivotally connected to the plate adjacent to the front of the heel, said supporting arm being curved around the heel, a strap secured to the upper end of the supporting arm by means of which the arm is secured to the leg of the wearer, a vertical tubular housing secured to the arm adjacent to the lower end thereof, a spring disposed within the arm and resting on said plate, normally urging the plate and shoe with which the arm is connected, to a position at right angles with respect to the arm,

and an adjusting screw by means of which the tension of the spring is regulated.
